CLAIM

The ornamental design for an automotive door, as shown and described.

DESCRIPTION

FIG. 1 is a right side perspective view of an automotive door showing our new design;

FIG. 2 is a front elevation view thereof;

FIG. 3 is a right side elevation view thereof;

FIG. 4 is a rear elevation view thereof; and,

FIG. 5 is a top and right side perspective view thereof.

The broken lines are shown for illustrative purposes only and form no part of the claimed design. The left door that is not shown is a mirror image of the door shown.
